UNITED STATES PATENT OFFICE.

PIERRE LEVESQUE, OF CHICAGO, ILLINOIS.

LIFE-SAVING SUIT AND SUPPORT THEREFOR.

Application filed May 22, 1925. Serial No. 32,158.

To all whom it may concern:

Be it known that I, PIERRE LEVESQUE, a subject of the King of England, residing at Chicago, in the county of Cook and State 5 of Illinois, have invented new and useful Improvements in Life-Saving Suits and Supports Therefor, of which the following is a specification.

This invention relates to life saving apparatus and has for its object the provision of a novel suit provided with buoying means and adapted to be worn by a life saver or other persons having occasion to dive or swim, the construction and arrangement of the garment being such that the wearer will be kept dry, except for the face and hands, and furthermore be kept warm, this latter mentioned feature having the advantage of preventing cramps and other 20 serious results by immersion in cold water.

An important object is the provision of a frame structure within which the suit is initially suspended in such position that the wearer may very quickly and easily don the 25 garment, the supporting structure being provided with lever operated releasing mechanism which will disengage the garment and act to save considerable time.

Another object of the invention is the 30 provision of an apparatus of this character well adapted for use at bathing beaches, on board-ship, at wharves or in fact at any place near the water, the device being always ready for instant service and it being 35 possible for the garment to be put on in a very few seconds as is of course necessary in case of emergency.

Fig. 1 is a perspective view of a life saving suit constructed in accordance with my 40 invention.

Fig. 2 is a vertical sectional view through the body portion,

Fig. 3 is a horizontal section taken on the line 3-3 of Fig. 2,

Fig. 4 is an elevation of the supporting frame illustrating the position of the suit, in the dotted lines,

Fig. 5 is a detailed side elevation of the frame, parts thereof being broken away and 50 illustrated in section,

Fig. 6 is a perspective view of the frame supporting the locking members,

Fig. 7 is a detailed side elevation of one of the supporting members,

Fig. 8 is a side elevation illustrating a 55 slightly modified form of frame,

Fig. 9 is a top plan view of the frame shown in Fig. 8,

Fig. 10 is a detailed section on the line 10-10 of Fig. 8, and

Fig. 11 is a perspective of one of the supporting plates on the frame shown in Fig. 8.

Referring more particularly to the drawings, and especially to Figures 1 to 3 inclusive, I have shown a garment designated broadly by the numeral 10, which garment includes a torso covering portion 11 and leg covering portions 12 which terminate in foot covering members 13. The torso covering portion 11 has attached thereto sleeves 14 and a yoke or shoulder engaging portion 15, the latter being of very elastic material so as to be capable of spreading open to a sufficient extent to permit the passage of the body of the wearer. The sleeves 14 terminate in cuffs 16 which are likewise of a very elastic material so as to permit the passage of the hands therethrough while ordinarily being sufficiently contracted to grip the wrists closely and prevent inlet of water at this point. If desired, the shoe or foot covering portion 13 may be weighted to a slight extent, or not, as preferred.

In order that the device may have buoyancy, it may be provided with a plurality of floats 17, of cork or other similar material located at the front of the torso engaging portion 11, or if preferred, these floats may be replaced by hollow inflatable 90 bag members 18 equipped with inflation tubes 19. If desired, a combination of both types of floats may be used as indicated at Figure 2.

The numeral 19' designates a collar which is relatively elastic and which is designed to be engaged about the neck portion 20 of the yoke 15 for the purpose of holding it about the neck of the wearer. This collar 19' is placed in position by being passed over the head of the user, and connected therewith is a flexible member 21 also connected with some suitable portion of the garment whereby to prevent the collar from becoming lost when the suit is not in use.

In order that the head of the wearer may be protected from becoming wet, use may be made of a cap 22 of rubber or the like capable of being stretched over the head in such manner as to leave the face exposed, and the edge of this cap is preferably provided with a bead 23 of sufficient

resilience to grip about the forehead and back of the head closely and prevent leakage of water. Connected with the cap is a flexible member 24 which is also connected with some suitable point on the garment for the purpose of holding the cap in position and preventing it from becoming lost when the suit is not in use.

The suit is designed to be used in connection with a supporting stand or frame illustrated in Figures 4 to 7 inclusive this stand being of such construction as to hold the suit in upright position ready for the lifeguard or other person to enter into it.

This stand is shown as comprising an upright rectangular frame 25 formed of or including any desired number of hollow bars or the like arranged at any suitable point and secured together in any desired manner. Suitably mounted on the frame are brackets 26 upon which are pivotally mounted arms 27 carrying depending hooks 28 adapted to be engaged within the neck portion of the suit for holding the suit suspended and for holding this neck portion expanded as indicated in Figure 4. Pivotally connected with the free or inner ends of the arms 27 are clevises 29 or the like, with which are pivotally connected depending bars or links 30.

Locked within the confines of the frame 25 is a U shaped member 31 which has its arms pivoted intermediate their ends, as shown at 32, and which is provided at its bight portion with bearing members 33 through which is journaled a rock shaft 34 having crank arms 35 thereon. At its central portion this rock shaft is provided with an upstanding finger 36 of angular formation normally engaging within a keeper 37 stationarily mounted on the frame. The bearing members 33 have their upper portions bifurcated as shown, and pivoted at 38 within these bifurcations are the lower ends of the links or bars 30. On the bight portion of the U shaped member 31 is a leaf spring 39 which bears against the finger 36 for normally holding the same in engagement with the keeper 37. Pivotally connected with the crank arm 35 are rods 40 which are located above the arms of the U shaped member 31 and which are connected with grips 41 pivotally mounted at 42.

Assuming that the life saving suit is suspended from the hooks 28 and located within the confines of the frame 25, whenever it is desired to don the suit the lifeguard or other persons steps into the garment then grasps the grips 41 and squeezes them toward the ends of the U shaped member 31 to rock the rock shaft 34 and move the finger 36 against the resistance of the springs 39 out of engagement with the keeper 37. The operator then pushes downwardly on the

ends of the U shaped member and this results in moving the bars or links 30 and swinging the arms 27 inwardly so that the hooks 28 will be disengaged from the neck portion of the garment, the person wearing this suit may then step out from the frame and may dive or swim without becoming wet except of course, the face and hands. Furthermore, the garment will operate to keep the wearer warm and prevent chilling and cramps in case the water is very cold.

In Figures 8 to 11 inclusive I have illustrated a slightly modified form of frame for supporting the garment in position and ready to be placed on the wearer. This frame comprises uprights 50 arranged in rectangular formation, the upper end of which are connected to a substantially rectangular frame 51. Arranged transversely of the frame 51 at each end thereof are rotatable shafts 52 having secured thereto the engaging hooks 53 which are adapted to engage with the neck portion of the garment for supporting the same in a suspended position.

The shafts 52 extend at one end beyond one side of the frame 51 and support the crank arms 54, one of the crank arms being connected to the upper end of the pivoted lever 55 by means of a link 56. The other crank arm is connected to the lever adjacent its lower end by means of a link 57. This lever 55 is pivotally mounted upon a supporting plate 58 attached to one side of the frame 51 whereby swinging movement of the lever 55 will rotate the shafts 52 in the opposite direction.

The lever 55 is retained in a normally vertical position by means of a pivoted catch 59 the upper end of which is engaged within the recess 60 formed in the lower end of the plate 58 and retained in this position by means of a coil spring 61 disposed between the handle 62 of the catch member and the handle 63 of the lever 55. It will be apparent that the catch member 59 is pivotally connected to the lever 55 as shown at 64 whereby the operator may readily grasp the two handles 62 and 63 and disengage the catch member from the recess 60 to permit lateral movement of the lever 55 in either direction.

In Figure 8 the hook members 53 are shown in position for supporting the suit by engaging the expandable neck portion. When it is desired to release the suit from the hooks the lever 55 is moved to the left swinging the hooks 53 inwardly toward each other disengaging the same from the neck of the suit.

From the foregoing description and a study of the drawings it will be apparent that I have thus provided a simply constructed, inexpensive and very efficient

device for the purpose specified which will be of great advantage to lifeguards and others and which on account of its peculiar suspension is capable of being put on in a 5 very few seconds, this feature being of great advantage in case of emergency.

While I have shown and described the preferred embodiment of the invention, it should be understood that I reserve the right 10 to make such changes in the form construction and arrangement of parts as will not depart from the spirit of the invention or the scope of the subjoined claims.

Having thus described the invention, I 15 claim:

1. In combination, a garment of impervious elastic material and a supporting stand for suspending the same in upright position, comprising a frame, arm members movably 20 mounted upon the frame, and means on said arm members engaging within a portion of the garment for holding the same distended.

2. In combination, a garment of impervious elastic material and a supporting stand 25 for suspending the same in upright position, comprising a frame, arm members movably mounted upon the frame, and means on said arm members engaging within a portion of the garment for holding the same distended, and lever operated means for releasing 30 said means.

3. In combination, a garment of imper-

vious elastic material, and a supporting stand for suspending the same including an upright frame, arms pivoted within the 35 frame and carrying hooks engaging within the neck portion of the garment for holding said neck portion expanded, and lever operated means connected with said arms for moving them out of engagement with the 40 garment.

4. A supporting stand for a life saving suit comprising an upright frame, arms pivoted within the frame and carrying hooks adapted for engagement with the garment at 45 the neck thereof for holding it expanded, a U-shaped member pivotally mounted within the frame, grip release locking means normally holding said U shaped member against movement, and means connected to 50 said member and with said arms for swinging the latter to disengage the hooks from the garment.

5. A supporting stand for life saving suits comprising a frame, movable hook members 55 carried by the frame whereby to normally engage the neck portion of the suit for holding it expanded and an operating lever having operative connection with the hooks whereby to manually move them out of en- 60 gagement with the neck portions of the suit.

In testimony whereof I affix my signature.

PIERRE LEVESQUE.
